BRIDGE GUARD

Carl G. Gottholm, Malden, Mass.

Application June 8, 1948, Serial No. 31,724

7 Claims. (Cl. 246—486)

1

This invention relates to an improvement in the safety device used on railroads called a bridge warning or bridge guard, and, more particularly, the invention relates to, and one of its objects is to provide, an improvement in the bridge guard disclosed and claimed in my prior Patent No. 2,392,529, issued January 8, 1946.

A further primary object of my invention is to provide an improved pendant construction particularly adapted for use in the bridge guard disclosed in my prior patent, whereby the construction of the tool that is used for removing and replacing the pendants is greatly simplified.

Another object of my invention is to provide a pendant formed of stiff metallic wire comprising a loop for supporting the same in a hanger loop of the bridge guard, said pendant loop being provided with a hooked end portion and having an angularly directed portion adjacent to and adapted to receive the hooked end portion of the pendant loop to maintain the pendant loop closed, said pendant also having a second loop preferably adjacent to or formed within the first mentioned loop thereof; and the novel subcombinations thereof.

Other and further objects of the invention will become apparent as the description proceeds, reference being made to the accompanying drawings forming a part of the present disclosure, wherein for purposes of illustration one embodiment of the invention is illustrated, and wherein:

Fig. 1 is an elevational view showing my bridge guard as it is customarily installed on a double track railroad.

Fig. 2 is an enlarged fragmentary elevational view showing my simple method of construction including the new pendant construction; and

Fig. 3 is a fragmentary perspective view of the tool with which a track workman can remove a defective pendant and replace it with a new one.

Referring to the drawings, the bridge guard, generally indicated by numeral 1, comprises a supporting wire 2, preferably in the form of a rope, one or more spacing hangers 3, and a plurality of pendants 4. The construction illustrated in Fig. 1 is for a double track railroad and it is obvious that the construction for more or less tracks is very similar.

The wire rope 2 is supported by means of posts 5 on opposite sides of the railroad tracks 6, and, as illustrated, the ends of the rope 2 are passed or looped through rings 7 secured to the upper end portions of the posts 5 and made secure as by means of clamps or the like 8.

The spacing hanger 3 is preformed from stiff metallic wire or wire-like material, comprises end loops 9, pendant supporting loops 10, and makes one complete turn around the supporting wire rope 2 between each of the hanger loops 10. The spacing hanger 3 snugly engages the wire rope 2 and is made in sections or units 11 convenient in length. These sections are assembled at the site where the bridge guard is to be installed by threading a sufficient number of the sections 11 on the wire rope 2. The sections are then firmly fastened to each other and to the wire rope by means of simple carriage bolts extended through the loops 9. Upon assembly, the hanger sections provide a very rigid construction and resist the tendency of the pendants 4 to swing up over the wire rope support, when struck by any means whatever.

The pendants 4 with which the tool illustrated in Fig. 3 is designed for use are formed of stiff metallic wire such as steel wire as were the pendants disclosed in my prior patent, but include some structural changes. Each of the pendants 4 comprises a relatively long piece of wire which is bent at one end to form an elongate supporting loop 13 adapted to be received in the hanger loops 10. The loop 13 has a hooked or curved free end portion 14 adapted to engage the pendant to maintain the loop closed. Preferably, the pendant is provided with an angularly directed portion 15 adjacent to and adapted to receive the curved end portion 14 of the loop. A second, preferably but not necessarily, closed and smaller elongate attachment loop 16 comprising side portions 17 is formed in the pendant 4 adjacent to, or as illustrated, in the portion of the pendant defining the loop 13. The major axes of the loops 13 and 16 are substantially at right angles to each other, and the attachment loop 16 is directed outward and away from the loop 13 so as not to interfere with the closing thereof.

My wire working tool is preferably constructed of metal, and in the embodiment illustrated in Fig. 3 comprises a tubular member 21 of any desired cross-sectional configuration, having an end wall 22 at one end thereof. A flattened, tubular member or loop holder 23 is secured to the end wall 22 as by means of a weld 24. The loop holder 23 provides an elongate recess 25 adapted to receive the wire loop 16 of the pendant, as will be later described in detail.

One end of a long, wooden, or tubular metal handle 26 is received within the tubular member 21, and in the embodiment illustrated, the

wall 22 functions to limit the inward movement of the handle and also provides a means connecting the loop holder 23 with the tubular member 21.

A radially directed, internally threaded, hollow boss or nut 27 surrounds an opening in the tubular member 21 and is suitably secured thereto as by means of a weld 28. An elongate bolt 29 having a threaded end 30 is received in the boss 27 for securing the tubular member 21 to the handle 26. The bolt 29 projects outwardly from the tubular member 21, preferably has a headed free end 31, and is used to perform an additional function which will be described in detail presently.

The attachment loop 16 of pendant 4 is adapted to be received in the recess 25 of the loop holder 23, as illustrated in Fig. 3, and preferably, the recess 25 is made slightly smaller than the normal width of the loop 16 so that the side portions 17 thereof will be resiliently urged into frictional contact with the end walls 33 of the loop holder 23. This frictional contact releasably but adequately secures the pendant 4 to the tool.

It frequently happens that a pendant 4 of the bridge guard or warning device 1 becomes damaged and must be replaced and it is for this purpose that the pendant and tool disclosed herein is particularly designed. A single track workman standing on the ground below the bridge guard, with this tool, can quickly remove a defective or damaged pendant 4 and replace it with a new one in the following manner:

To remove a defective pendant 4, the handle 26 is elevated and the bolt 29 is inserted in the closed loop 13 thereof in a direction towards the plane of the drawing. The tool is then given approximately a quarter turn counter-clockwise, the loop 13 snaps open as shown in the drawing at the left of Fig. 2, and the pendant can readily be lifted out of the hanger loop by the bolt 29.

To place or replace a pendant, the loop 16 of the pendant is positioned in the recess 25 of the loop holder 23 as illustrated in Fig. 3, the loop 13 being open and the free end 14 thereof up or in position to be readily inserted into the hanger loop. Then the tool with the pendant projecting outwardly as shown is raised by the handle 26 to the proper height and the free end 14 of the loop 13 is inserted into the hanger loop 10. Preferably, the loop 13 is hooked through the hanger loop 10 all the way, and the handle 26 is then pulled downwardly to release the tool from the pendant, leaving the pendant hanging with the loop 13 open. The bolt 29 is then inserted in the open loop 13 in a direction outwardly from the plane of the drawing, given approximately a quarter turn counter-clockwise, and the end 14 of the loop snaps over the inclined portion 15 of the pendant to close the loop 13 securely.

The wire working tool disclosed herein is disclosed and claimed in my copending application Serial No. 22,609 filed April 22, 1948, now Patent No. 2,488,396 dated November 15, 1949.

In the foregoing disclosure I have illustrated and described only the preferred embodiment of my invention, but it is to be understood that this disclosure is given by way of illustration and not in limitation of the invention, and that I desire to cover any equivalent or modified forms of the invention as come within the scope of the appended claims.

I claim:

1. In a bridge guard comprising a supporting wire rope and a spacing hanger made of stiff

metallic wire having hanger loops, said hanger being wound around said supporting wire rope, a plurality of pendants each made of a stiff metallic wire, each of said pendants having two elongate loops, the major axes of said two loops being at substantially right angles to each other, one of said two loops being a supporting loop for supporting the pendants in the hanger loops and having a hooked free end portion movable to positions opening and closing said supporting loop, said supporting loop being adapted to be closed by twisting said free end portion around the pendant portion of said supporting loop, said pendant portion of said supporting loop being angularly directed to maintain said supporting loop closed, the other of said two loops being an attachment loop for holding the pendants with said supporting loop in open position for positioning the pendants in the hanger loops, and said attachment loop being directed outward and away from said supporting loop whereby not to interfere with the closing thereof.

2. In a bridge guard comprising a supporting wire rope and a spacing hanger made of stiff metallic wire having hanger loops, said hanger being wound around said supporting wire rope, a plurality of pendants each made of a stiff metallic wire, each of said pendants having two elongate loops, the major axes of said two loops being at substantially right angles to each other, one of said two loops being a supporting loop for supporting the pendants in the hanger loops and having a hooked free end portion movable to positions opening and closing said supporting loop, said supporting loop being adapted to be closed by twisting said free end portion around the pendant portion of said supporting loop, the other of said two loops being an attachment loop for holding the pendants with said supporting loop in open position for positioning the pendants in the hanger loops, and said attachment loop being directed outward and away from said supporting loop whereby not to interfere with the closing thereof.

3. In a bridge guard comprising a supporting wire and a spacing hanger having hanger loops, said hanger being wound around said supporting wire, a plurality of pendants each made of a stiff metallic wire, each of said pendants having two elongate loops, the major axes of said two loops being at substantially right angles to each other, one of said two loops being a supporting loop for supporting the pendants in the hanger loops and having a hooked free end portion movable to positions opening and closing said supporting loop, said supporting loop being adapted to be closed by twisting said free end portion around the pendant portion of said supporting loop, said pendant portion of said supporting loop being angularly directed to maintain said supporting loop closed, the other of said two loops being an attachment loop for holding the pendants with said supporting loop in open position for positioning the pendants in the hanger loops, and said attachment loop being directed outward and away from said supporting loop whereby not to interfere with the closing thereof.

4. In a bridge guard comprising a supporting wire and a spacing hanger having hanger loops, said hanger being wound around said supporting wire, a plurality of pendants each made of a stiff metallic wire, each of said pendants having two elongate loops, the major axes of said two loops being at substantially right angles to each other,

one of said two loops being a supporting loop for supporting the pendants in the hanger loops and having a hooked free end portion movable to positions opening and closing said supporting loop, said supporting loop being adapted to be closed by twisting said free end portion around the pendant portion of said supporting loop, the other of said two loops being an attachment loop for holding the pendants with said supporting loop in open position for positioning the pendants in the hanger loops, and said attachment loop being directed outward and away from said supporting loop whereby not to interfere with the closing thereof.

5. A pendant for a bridge guard made of an elongate stiff metallic wire, said pendant having two elongate loops, the major axes of said two loops being at substantially right angles to each other, one of said loops being a supporting loop for supporting the pendant on the bridge guard and having a hooked free end portion movable to positions opening and closing said supporting loop, said supporting loop being adapted to be closed by twisting said free end portion around the pendant portion of said supporting loop, said pendant portion of said supporting loop being angularly directed to maintain said supporting loop closed, the other of said loops having an attachment loop for holding the pendant with said supporting loop in open position for positioning the pendant on the bridge guard, said attachment loop being directed outward and away from said supporting loop whereby not to interfere with the closing thereof.

6. A pendant for a bridge guard made of an elongate stiff metallic wire, said pendant having two elongate loops, the major axes of said two loops being at substantially right angles to each other, one of said loops being a supporting loop for supporting the pendant on the bridge guard and having a hooked free end portion movable to

positions opening and closing said supporting loop, said supporting loop being adapted to be closed by twisting said free end portion around the pendant portion of said supporting loop, the other of said loops being an attachment loop for holding the pendant with said supporting loop in open position for positioning the pendant on the bridge guard, and said attachment loop being directed outward and away from said supporting loop whereby not to interfere with the closing thereof.

7. A pendant for a bridge guard made of an elongate stiff metallic wire, said pendant having two elongate loops, the major axes of said two loops being at substantially right angles to each other, one of said loops being a supporting loop for supporting the pendant on the bridge guard and having a hooked free end portion movable to positions opening and closing said supporting loop, said supporting loop being adapted to be closed by twisting said free end portion around the pendant portion of said supporting loop, the other of said loops being an attachment loop for holding the pendant with said supporting loop in open position for positioning the pendant on the bridge guard, and said attachment loop being formed in said supporting loop and being directed outward and away from said supporting loop whereby not to interfere with the closing thereof.
